UNITED STATES PATENT OFFICE.

OTTO L. BRUBAKER, OF SAN JOSE, CALIFORNIA, ASSIGNOR TO AUGUSTUS M. TUREL,
OF SAN JOSE, CALIFORNIA.

CARTRIDGE ADAPTER AND AMMUNITION THEREFOR.

Application filed September 24, 1923. Serial No. 664,435.

To all whom it may concern:

Be it known that I, Otto L. BRUBAKER, a citizen of the United States, and resident of San Jose, Santa Clara County, California, have invented new and useful Improvements in Cartridge Adapters and Ammunition Therefor, of which the following is a specification.

My invention has for its object a device 10 adapted to be inserted in the chamber of a shotgun whereby the shotgun may be employed for discharging cartridges and also blank cartridges with a small charge of shot and is particularly applicable for practice 15 shooting and for the killing of farm pests.

By referring to the accompanying drawings and specifications my invention will be readily understood.

Referring to the accompanying drawing: 20 Figure 1 shows a side view of my cartridge adapter.

Figures 2 and 3 are end views of Figure 1.

Figure 4 is an enlarged longitudinal section of the device of Figure 1.

Figures 5 and 6 are enlarged fragmentary longitudinal sections showing the adapter being employed with a rifle cartridge and with a blank cartridge and charge of shot respectively.

Figure 7 shows the adapter in the act of ejecting an expended shell.

Throughout the figures the same numerals refer to identical parts. A body portion of my adapter is shown at 1, having a threaded 35 extension 2 with which an ejector collar 3 is engaged. The bore 4 is adapted to pass the bullet 5 with the exception of the rifling 6 and 7, which projects sufficiently into the bore to provide the necessary twisting 40 impulse whereby the bullet 5 when ejected from the cartridge 8 follows a spiral path as well known in conventional rifle bores. The bore 4 is relieved at 9 for the shell 8, which, when forced into position, as shown 45 in Figures 4 or 5, frictionally engages at 10 on a suitable reduced bore provided by the riflings 6, 7. It is understood that the adapter as shown in Figures 4, 5 or 6 is made to fit the shell chamber of any conven-

tional shotgun, the outer surface 11 freely 50 entering the said chamber so that the firing pin of the gun, well known but not shown, impinges upon the cap 12 to discharge the cartridge 8. The shell is then ejected by unscrewing the collar 3 a sufficient amount 55 upon the threaded portion 2 to disengage the shell from its frictional engagement at 10, all as shown in Figure 7 when the shell 60 freely falls out of the adapter and the collar 3 is again screwed into the position of Figure 4 and a new charge inserted. Milled surfaces are provided at 20, 21 to facilitate handling the parts.

Referring particularly to Figure 6 a blank cartridge is shown at 13 which fits 65 the adapter exactly the same as the shell 8 of Figures 4 and 5; and in advance thereof is shown a capsule 14 filled with conventional shot 15, the capsule frictionally engaging against the rifling 6, 7 and is held 70 in place after being forced against the rifling by the cartridge 13, in the position shown in the figure. When the cartridge 13 is discharged the shot is propelled through the bore 4. Such ammunition I have found 75 to be well adapted to the killing of small birds and the protection of growing crops and trees from the usual farm pests.

I claim:

1. In combination with a cartridge 80 adapter, a blank cartridge, and a separate gelatin capsule charged with shot.

2. In combination with a cartridge adapter, a blank cartridge, and a separate 85 gelatin capsule charged with shot said capsule comprising two hemispherical end sections telescoped together.

3. In combination with a cartridge adapter, a blank cartridge, and a separate 90 gelatin capsule charged with shot frictionally engaging the bore of said adapter.

4. In combination with a cartridge adapter, a blank cartridge, and a separate 95 gelatin capsule charged with shot said capsule comprising two hemispherical end sections telescoped together frictionally engaging the bore of said adapter.

OTTO L. BRUBAKER.
